UNITED STATES PATENT OFFICE.

JOHN ALBERT FERGUSON, OF DENVER, COLORADO.

BUILDING-BLOCK AND WALL.

SPECIFICATION forming part of Letters Patent No. 733,928, dated July 14, 1903.

Application filed April 18, 1903. Serial No. 153,326. (No model.)

To all whom it may concern:

Be it known that I, JOHN ALBERT FERGUSON, a citizen of the United States of America, residing in the city and county of Denver and State of Colorado, have invented certain new and useful Improvements in Building-Blocks and Walls; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in building-blocks and walls; and it consists of the features hereinafter described and claimed, all of which will be fully understood by reference to the accompanying drawings, 20 in which is illustrated an embodiment thereof.

In the drawings, Figure 1 is a detail view in perspective of my improved building-block. Figs. 2 to 5, inclusive, show a number of different arrangements of the block that may be 25 employed in the formation of walls therefrom.

The same reference characters indicate the same parts in all the views.

Let A designate my improved building-block in its entirety. This block consists of 30 a body part A', end projections A², and an intermediate projection A³. The said projections extend from the inner surface of the block and are of a height equal to half that of the body of the block. The projection A³ is equidistant from the projections A² and is 35 twice the thickness of either projection A², the projections A² being of equal thickness. In referring to the thickness of the projections the distance through them measured on 40 a horizontal line lengthwise of the block is intended.

When the blocks are used in the construction of walls, they may be combined in a variety of ways. As shown in Fig. 2, two of the 45 blocks are so placed that their projections interlock and coincide vertically, the two united blocks occupying reverse positions on opposite sides of the wall. The two block members A when united as just explained form a duplex block having rectangular sides and 50 ends. These duplex blocks are placed end to end, and they are arranged in vertical

courses to break joints. (See Fig. 2.) This figure shows the wall bonded in courses with horizontal joints extending through the wall, the blocks breaking joints in alternate courses.

In the construction shown in Fig. 3 the wall is formed by placing the blocks A end to end on opposite sides of the wall. In this case the projections interlock, as in Fig. 2, the only difference being the arrangements for breaking the joints. By virtue of this arrangement the adjoining end projections of any two blocks interlock with and engage the central projection of the opposite block or the block on the opposite side of the wall. In this view the wall is bonded in courses with horizontal joints extending through the wall, the blocks on one side of the wall breaking joints with those on the opposite side and also with each other.

In the construction shown in Fig. 4 the blocks are vertically staggered on opposite sides of the wall, whereby they are made to break joints horizontally. This construction shows a pier one block in length with the horizontal joints broken, the inner blocklapping on the outer block, so that the horizontal joints do not go through the wall.

The wall construction shown in Fig. 5 is a combination of the arrangements shown in Figs. 3 and 4, whereby the blocks A are vertically staggered and arranged to break joints both horizontally and vertically. This view shows a portion of a wall with the blocks on the inner side of the wall breaking joints endwise with the blocks on the other side of the wall. The horizontal joints are broken, so that no horizontal joint extends through the wall.

Having thus described my invention, what I claim is—

1. A building block or member comprising a body part having end and intermediate projections extending therefrom at right angles to the body of the block, the said projections having a height equal to half that of the body of the block.

2. A building-block comprising a body part having end and intermediate projections extending therefrom at right angles thereto, the said projections having a height equal to half that of the body of the block, the intermediate projection being equidistant from

the end projections and of twice the thickness of the end projections measured in a horizontal line extending lengthwise of the block.

5 3. A wall composed of blocks having projections extending at right angles to the body of the block and of less height than the body part, the said blocks being reversed and united to form opposite sides of a wall, the projections being arranged to coincide and interlock, and the courses being arranged one above another to break the vertical joints.

4. A wall composed of building-blocks having a body part provided with projections extending at right angles thereto and of a less height than the body part, the said blocks having their vertical position reversed on opposite sides of the wall, and their projections being interlocked to break the vertical joints of a single course.

5. A wall composed of building-blocks having a body part, and projections extending at right angles to the body part and of half the height of the body part, the blocks being vertically arranged in stepped or staggered fashion, to break the horizontal joints of the vertical courses. 25

6. A wall composed of building-blocks having a body part and projections extending at right angles to the said part and of half the height thereof, the blocks being vertically arranged in stepped fashion, to break the horizontal and vertical joints of the different courses. 30

In testimony whereof I affix my signature 35
in presence of two witnesses.

JOHN ALBERT FERGUSON.
